UNITED STATES PATENT OFFICE.

CHARLES COESTER, JR., OF BRIDGEPORT, CONNECTICUT.

DESIGN FOR A TOY FOR EXPLODING CAPS AND FULMINATES.

SPECIFICATION forming part of Design No. 12,733, dated February 7, 1882.

Application filed July 7, 1881. Term of patent 14 years.

To all whom it may concern:

Be it known that I, CHARLES COESTER, Jr., of Bridgeport, in the county of Fairfield and State of Connecticut, have originated a new 5 Design for a Toy for Exploding Caps and Fulminates, of which the following is a specification.

My design relates to toys for exploding paper and other caps and fulminates.

10 The design consists in making the hand-piece in the form of a fire-arm and the cap or fulminate receptacle in the form of a figure having a resemblance to a human being, substantially as hereinafter set forth.

15 The design further consists in making the hand-piece in the form of a fire-arm and a hammer in the form of part of a figure having a resemblance to a human being, substantially as hereinafter set forth.

20 The design further consists in making the hand-piece in the form of a fire-arm, the cap or fulminate receptacle in the form of a figure having a resemblance to a human being, and the hammer in the form of part of a figure having a resemblance to a human being, substantially as hereinafter set forth.

The accompanying drawing represents a side view of a toy for exploding caps and fulminates embodying my design.

25 A designates a hand-piece made in the form of a fire-arm.

B designates a cap or fulminate receptacle made in the form of a figure resembling a human being, and mounted on the top of the barrel-like portion of the hand-piece. It is made

30 in the form of a Chinaman walking or running along the said barrel-like portion of the hand-piece. The cap or fulminate receptacle

is located at the portion b, which represents the mouth of the Chinaman, and the movable 40 part is made in the form of his lower jaw, so that when it operates to explode the caps or fulminates it will have the appearance of biting the same.

C designates the hammer. It forms part of 45 a figure resembling a human being. The figure shown represents an Irishman, and the hammer is made in the form of a leg, c, which operates with a kicking movement. The other leg, c', of the Irishman forms his support, and 50 is erected on the barrel-like portion of the hand-piece. A catch, a, controls the operation of the kicking leg c of the Irishman, and is made in the form of a trigger, and occupies the position of an ordinary trigger with relation to the hand-piece A.

My design imparts to a toy for exploding caps and fulminates a very ludicrous appearance, and makes the toy a source of great amusement to children using it.

60 What I claim as my design, and desire to secure by Letters Patent, is—

1. The design for the hand-piece and cap or fulminate receptacle of a toy for exploding caps and fulminates, substantially as set forth.

65 2. The design for the hand-piece and hammer of a toy for exploding caps and fulminates, substantially as set forth.

3. The design for hand-piece, cap or fulminate receptacle, and hammer of a toy for exploding caps and fulminates, substantially as 70 set forth.

CHARLES COESTER, JR.
